(57) **CLAIM**

The ornamental design for a container body portion, as shown and described.

DESCRIPTION

FIG. 1 is a top, front, and right side perspective view of a first embodiment of a container body portion of the present invention;

FIG. 2 is a front elevational view thereof, the rear elevation view being identical;

FIG. 3 is a top plan view thereof;

FIG. 4 is a bottom plan view thereof;

FIG. 5 is a top, front, and right side perspective view of a second embodiment of a container body portion of the present invention;

FIG. 6 is a front elevational view thereof, the rear elevation view being identical;

FIG. 7 is a top plan view thereof; and,

FIG. 8 is a bottom plan view thereof.

The dash-dash-dash broken line showing of the container bottom portion and of the closure are included for the purpose of showing environmental structure that forms no part of the claimed design.

The dot-dash-dot-dash broken lines shown in the drawings define the boundaries of the claimed design.
